[57] CLAIM

The ornamental design for a video game console, substantially as shown and described.

DESCRIPTION

FIG. 1 is a perspective view of a video game console showing my new design. The dust cover portion of the console is shown raised above the main housing to illustrate the underlying design features;

FIG. 2 is a front elevation thereof;

FIG. 3 is a rear elevation thereof;

FIG. 4 is a right side elevation thereof, the left side elevation is a mirror image of that depicted;

FIG. 5 is a top plan view of the main housing illustrated in FIG. 1; and

FIG. 6 is a bottom plan view thereof.
